CLAIM

The ornamental design for a housing for an electrical connector, as shown and described.

DESCRIPTION

FIG. 1 is a perspective view of our housing for an electrical connector.

FIG. 2 is a front elevation view thereof.

FIG. 3 is a right elevation view thereof, the left being a mirror image.

FIG. 4 is a top plan view thereof.

FIG. 5 is a rear elevation view thereof.

FIG. 6 is a bottom plan view thereof.

FIG. 7 is a section view taken along line 7—7 of FIG. 3;
FIG. 8 is a section view taken along line 8—8 of FIG. 3.
